CLAIM

The ornamental design for a car seat arm pad, as shown and described.

DESCRIPTION

This application relates to the Car Seat Cover System design patent application U.S. Ser. No. 29/635,941 filed Feb. 5, 2018, herein incorporated by reference.

FIG. 1 is a perspective view taken from the front, left side and top side of the car seat arm pad of the present design, shown attached to a handle of a car seat, in accordance with the present design.

FIG. 2 is a front elevation view of the car seat arm pad shown in isolation.

FIG. 3 is a rear elevation view of the car seat arm pad shown in isolation.

FIG. 4 is a left side elevation view of the car seat arm pad shown in isolation.

FIG. 5 is a right side elevation view of the car seat arm pad shown in isolation.

FIG. 6 is a top plan view of the car seat arm pad shown in isolation.

FIG. 7 is a top plan view of the car seat arm pad shown flat in an open position; and,

FIG. 8 is a bottom plan view of the car seat arm pad shown flat in an open position.

The dash-dot-dash broken lines shown illustrate environmental structures and form no part of the claimed design. Elements drawn in broken dash-dot lines are included for illustrating portions of the car seat arm pad, and form no part of the claimed design.

1 Claim, 5 Drawing Sheets
